PARKING METER CASING

Gerald A. Hale, Oklahoma City, Okla.

Application April 8, 1948, Serial No. 145,604

Term of patent 14 years

(Cl. D52—3)

To all whom it may concern:

Be it known that I, Gerald A. Hale, a citizen of the United States, residing at Oklahoma City, in the county of Oklahoma and State of Oklahoma, have invented a new, original, and ornamental Design for a Parking Meter Casing, of which the following is a specification, reference being had to the accompanying drawing, forming part thereof.

The figure is a perspective view of a parking meter casing, showing my new design. The side of the parking meter not disclosed is the same in appearance as the side shown.

I claim:

The ornamental design for a parking meter casing, as shown and described.

GERALD A. HALE.
